UNITED STATES PATENT OFFICE.

LOUIS STANKEWITZ, OF NEW YORK, N. Y.

TOBACCO-BOX.

1,232,404.

Specification of Letters Patent.

Patented July 3, 1917.

Application filed December 2, 1913. Serial No. 804,287.

To all whom it may concern:

Be it known that I, LOUIS STANKEWITZ, a subject of the Emperor of Austria-Hungary, residing at New York, in the county of New York and State of New York, have invented new and useful Improvements in Tobacco-Boxes, of which the following is a specification.

The invention relates to tobacco, and has 10 for an object to provide a box or receptacle for containing tobacco.

The invention contemplates, among other features, the provision of a box preferably made of stamped metal to provide a container for tobacco and a receptacle for matches, the receptacle forming a part of the box or container and so arranged with respect thereto that the entire structure will not be of a bulky configuration; will present 20 a neat and effective appearance and will conveniently hold matches so that they can be readily used when desired.

In the further disclosure of the invention reference is to be had to the accompanying 25 drawings, constituting a part of this specification, in which similar characters of reference denote corresponding parts in all the views, and in which:

Figure 1 is a perspective view of the box, 30 showing the match receptacle open to disclose the manner of arranging the matches therein;

Fig. 2 is a vertical transverse sectional view taken through the box when the cover 35 of the match receptacle is in closed position;

Fig. 3 is a horizontal transverse sectional view taken through the box when the cover is in closed position.

Referring more particularly to the views, 40 I provide a tobacco box 10, preferably in the nature of an elongated container body 11 which is preferably made of stamped metal and which has a swinging cover 12 normally closing one end of the container body 11. 45 The front face of the container body 11 is adapted to provide a receptacle 13 for matches 14 and the receptacle 13 is formed by striking a depression 15 in the front face of the container body 11 as shown, the said 50 depression being preferably of a rectangular configuration and made sufficiently deep so that the matches 14 preferably carried by a suitable holder 16 can be arranged to repose within the receptacle and lie below the front 55 face of the container body 11. Suitable securing members 17 in the nature of wires

are adapted to be passed through the holder 16 having the matches 14 thereon and also passed through apertures 18 in the wall of the depression 15 and which forms a part 60 of the front wall of the container body, with the ends of the securing members bent against the inner face of the container body so as to rigidly secure the holder 16 within the receptacle 13.

A cover 19 is provided for the receptacle 13 and is also preferably made of sheet metal, the said cover having its inner longitudinal edge curled to provide a hinge member 20, through which is adapted to be 70 passed a suitable pintle 21 having its ends journaled in upper and lower walls 22, 23 of the receptacle 13 and which walls are formed by portions of the front face of the container body 11 when the depression 15 is 75 struck therein. At its medial portion the inner curled edge of the cover 19, forming the hinge member 20, is formed to provide a spring-like tongue 24, which is adapted to 80 abut against a wall of the receptacle 13 when the cover 19 is in closed position so that upon releasing the cover the same will spring into open position by the spring-like action of the said tongue bearing against the wall of the container body as mentioned.

A notch 25 is preferably formed in an opposite wall of the receptacle at its point of formation with the front wall of the container body, and a projection 26 is provided on the cover 19, in the nature of a grip, said 90 projection being adapted to be received in the notch 25 to lock the cover in closed position. By simply pressing against the front wall of the container body adjacent the notch, the projection will be released from 95 engagement with the container body at the notch, thus, through the spring-like action of the tongue 24, causing the cover to swing into open position.

As mentioned heretofore, the matches 14 100 are preferably carried by a holder 16 and the holder and matches, as shown, are made of paper or some other suitable inflammable material, with the holder and matches integral and the matches so arranged with respect to the holder that they can be torn or removed from the holder when it is desired to use the same. The inner face 27 of the cover 19 is preferably roughened to provide a match scratching surface and upon which 110 the matches 14 can be scratched when they are removed from the holder for the purpose

of lighting tobacco which has been removed from the container body 11.

As mentioned heretofore, the receptacle 13 is formed by simply striking inwardly a portion of the front face of the container body, and in the preferred form of my device the cover for the receptacle is preferably made of the same material as the container body and which, in most instances, is 10 a sheet metal of a flexible nature. The box 10 is preferably constructed so that it will readily fit into the pocket and can be arranged and designed to contain cigars as well as plug or loose tobacco.

15 Having thus described my invention, I claim:

The combination with a receptacle having one wall depressed to form a rectangular

recess, of a positively pivoted cover therefor, said cover comprising a flap having one edge 20 curled to provide hinging members for the reception of a pintle, the ends of said pintle being journaled in the end walls of the recess, a spring tongue formed integral with said cover and engaging one of the walls of 25 the recess to normally force the said cover open and means carried by the cover and engageable with the receptacle to hold said cover in a closed position.

In testimony whereof I affix my signature 30 in presence of two witnesses.

LOUIS STANKEWITZ.
